The present invention relates to a vacuum sputtering pump.

For the purpose of producing and maintaining a vacuum, vacuum pumps have lately been employed in which the gases to be eliminated are either chemically or mechanically bound instead of being conveyed by the pump to the atmosphere in the conventional manner. This may be done either by freezing out the gases, that is, by converting them into a solid state or by chemically binding them by means of a getter material. For producing the getter layer, two methods are especially known, namely, by vacuum evaporation or by cathode sputtering by means of a gas discharge, that is, by an ion bombardment.

The present invention relates to the last-mentioned method of cathode sputtering and more particularly to the elimination of the so-called "memory effect" which occurs in this method. Such sputtering pumps are at present very frequently employed, especially because they have two very important advantages over the pumps which operate by means of evaporation:

(1) The ionization of the gas molecules occurs by a self-sustained discharge and does not require a hot cathode which only lasts for a limited length of time and is often the cause of trouble. Such sputtering pumps can therefore also be employed for very long periods of time at higher pressures of, for example, 10^{-6} mm. Hg without any decrease in their efficiency.

(2) Since the gas-discharge current and thus also the amount of titanium which is sputtered within a certain unit of time is proportional to the pressure in the pump or in the apparatus which is connected thereto, the sputtering of the titanium adjusts itself automatically to the amount of gas which is to be pumped off without requiring any special electronic or mechanical means.

However, certain difficulties occur in sputtering pumps if rare gases and also other gases which do not chemically combine with the getter metal are to be pumped off. When in the ionized condition, the rare gases are largely taken up by the getter material. On the other hand, it is also possible to bind neutral rare gas atoms by a getter layer if such an amount of getter material is constantly condensed so that the rare gas atoms will be "buried" thereby.

In a sputtering pump, the rare gas ions are taken up to the largest extent by the cathode. However, since the cathode is subjected to a constant bombardment of ions, not only titanium is sputtered but the gases which have already been taken up by the cathode are again freed. Therefore, at regular intervals of a few minutes undesirable pressure increases occur which are due to the fact that these gases are again liberated from the cathode. This is called the "memory effect" which means that the pump "remembers" what it has once before pumped off.

This memory effect is of very minor importance to the chemically active gases which are primarily taken up and chemically bound by the coating of titanium which is formed on the entire inner walls of the pump. At the occurrence of rare gases, however, the efficiency of the sputtering pump decreases considerably as the result of its memory effect.

2

While in a getter ion pump with a thermal evaporation of the getter metal it is possible by producing a high rate of evaporation to bury the rare gases which have once been taken up by the getter layer by means of the newly condensed getter material, this is not possible in a sputtering pump since the rate of sputtering in such a pump changes merely when a change in pressure occurs but is otherwise fixed and cannot be changed arbitrarily.

This fact has already been recognized in the art and attempts have therefore been made to reduce the "memory effect" by making the cathode of a very particular outer shape or by providing not merely the two electrodes which are absolutely necessary, i.e., the anode and the cathode, but a further third electrode. This third electrode is connected to such a voltage that ions impinge thereon with a low energy and therefore only a small number of already "bound" rare gas atoms are knocked out of it. The two sputtering electrodes which are arranged symmetrically to the anode are of a honeycomb structure, while the cathode is generally located outside of the three mentioned electrodes and serves, for example, as an outer housing. These auxiliary cathodes are mounted opposite to the actual cathode and are given a negative potential so that the part of the gas ions which flows through the honeycombed auxiliary cathodes is retarded by the electric field which prevails between the cathode and the auxiliary cathodes. Since the gas ions then impinge upon the cathode with a relatively low energy, the memory effect becomes less prevalent.

However, insofar as rare gases are concerned, the ions and atoms which are taken up by the cathode are not sufficiently retained since the rate of sputtering of the titanium of the auxiliary electrode is too low and cannot be increased arbitrarily. Although the memory effect of this pump is reduced, it still exists and limits the best possible vacuum which may be attained as well as the constancy thereof.

It is an object of the present invention to overcome this disadvantage by employing in a sputtering pump at least one electrode of a material which is sputtered considerably more rapidly than titanium. Such materials are, for example, silver and copper. With such an electrode it is possible to cover the getter layer which contains rare gases from time to time with a thicker layer of the more rapidly sputtered material and thus to bury the rare gas atoms finally so that the layer will no longer show a memory effect.

The features and advantages of the present invention will become more clearly apparent from the following 50 detailed description of several embodiments thereof which is to be read with reference to the accompanying drawings, in which:

FIGURES 1 to 3 diagrammatically illustrate sputtering pumps with two groups of electrodes;

FIGURE 4 shows a sputtering pump with three groups of electrodes; while

FIGURE 5 shows a circuit diagram for operating a pump of the type as illustrated in FIGURE 2.

The sputtering pump as illustrated in FIGURE 1 is 60 contained within a housing 1 which is connected by a pipe socket 2 to the container which is to be evacuated. Of course, it is also possible to mount the pump system as illustrated as well as other necessary parts directly within the container which is to be evacuated, in which case the housing 1 may be omitted.

At the inside of housing 1, the electrodes 4, 5, and 6 are mounted. The electrodes 4 and 6 consist of solid metal, while the electrode 5 has a honeycomb structure. The electric lines 7, 8, and 9 leading to these electrodes are passed through the wall of housing 1 by means of vacuum-tight, insulated leadins 10, 11, and 12, respectively. The magnetic field which is required for the oper-

ation of the pump is produced by the magnet pole pieces 15 and 16.

The central electrode 5 which is mounted opposite to the sputtering electrodes 4 and 6 is provided with a positive potential and therefore serves as the anode, while the two other electrodes 4 and 6 have a negative potential and therefore form the cathodes. One of the cathodes, for example, the left cathode 4, consists of the getter metal titanium or is at least provided with a thick coating of this metal, while the other cathode, for example, the right cathode 6, consists according to the invention of a material, for example, silver, which is more easily sputtered than the getter material titanium. The cathode 6 may, however, also consist of a different material and only be provided with a thick coating of silver.

The operation of the sputtering pump according to FIGURE 1 is as follows:

Due to the potential distribution and the magnetic field which is provided, gas discharges occur, each of which passes through one of the open cells of the honeycomb electrode 5. For this purpose, the getter electrode 4 is given a higher negative potential than the electrode 6 which consists of the easily sputtered material. As the result of this, the ions impinge upon the getter electrode 4 with a considerably greater energy than upon the electrode 6 and thereby sputter the getter material which is condensed in the honeycomb cells of the electrode 5 and on the inner walls of housing 1 and thereby reacts chemically with parts of the gases which are to be pumped off. Even rare gases are then at least partly buried.

After larger amounts of rare gases have been pumped off and there is the danger that the memory effect might occur, the electrode 6 is supplied with the same or a higher negative potential than the electrode 4. High-energy ions then impinge upon the electrode 6 which is accordingly strongly sputtered. The sputtered material then covers the previous getter layers and thereby also buries the rare-gas atoms which are contained in these layers. These buried rare-gas atoms can therefore no longer emerge and cause a memory effect. After a certain length of time which may be easily determined by tests, the original potential values are again supplied and the pump is again operated in the normal manner.

FIGURE 2 illustrates a very simple and advantageous modification of the apparatus according to FIGURE 1. In this apparatus, the getter electrode 4 and the other electrode 6 are each divided into at least two parts which are mounted symmetrically to the anode 5. The manner of operation as described above with reference to FIGURE 1 may also be applied to this arrangement. It is, however, more advantageous not to apply negative potentials of different values simultaneously to both pairs of electrodes 4 and 6, but to apply a negative potential only either to the pair of electrodes 4A, 4B or to the pair 6A, 6B. The effect attained is the same as just described since the sputtered material is condensed at all points substantially uniformly.

FIGURE 3 illustrates a pump system with two normal groups of electrodes, wherein the pair of cathodes 20A, 20B of getter material is mounted at the opposite sides of the honeycombed anode 5. In addition to these electrodes a pair of auxiliary electrodes 22A, 22B is provided which consists of a more easily sputtered material and is likewise of a honeycomb structure. The cells of this structure are preferably equal to those of the anode 5. The operation and the effect of this pump correspond to those as described with reference to FIGURE 1. It may, however, be advisable to make the central electrode 5 of the pump according to FIGURE 3 of an easily sputtered material and to operate it as an auxiliary electrode, while the pair of electrodes 22A, 22B serves as the anode.

FIGURE 4 shows the electrode system of a vacuum sputtering pump of the type which is known as a three-electrode pump, in which the present invention is ap-

plied. The conventional three-electrode pump consists of an anode 5 of a honeycomb structure, a pair of auxiliary cathodes 25A, 25B also of a honeycomb structure which consist of a getter material, for example, titanium, and are mounted symmetrically to the anode 5, and a pair of cathodes 24A, 25B which are likewise mounted symmetrically to the anode and are supplied with a higher electric potential than the auxiliary cathodes 25A, 25B. Cathodes 24A, 24B may also form the housing of the pump or they may form a coating of an electrically conductive material on the pump housing. At the outside of the pump housing, a pair of magnet pole pieces 15 and 16 are also provided similarly as shown in FIGURES 1 to 3. According to the invention, this three-electrode pump is further provided with an additional pair of electrodes 26A, 26B which are likewise of a honeycomb structure and are mounted symmetrically to the anode 5. In the particular embodiment of the invention as shown in FIGURE 4, these additional electrodes 26A, 26B are inserted between the anode 5 and the auxiliary cathodes 25A, 24B. These electrodes 26A, 26B consist of a material, for example, silver or copper, which is more easily sputtered than the getter material of the auxiliary electrodes 25A, 25B.

The operation of the pump according to FIGURE 4 is as follows:

In the normal operation, the pair of electrodes 26A, 26B of the easily sputtered material is supplied with the same potential as the anode 5, while the auxiliary cathodes 25A, 25B are supplied with a lower potential than anode 5. The cathodes 24A, 24B are supplied with a higher potential than the auxiliary cathodes 25A, 25B. Under the influence of the electric field between the auxiliary cathodes 25A, 25B and the anode 5, the ions which are formed in the pump by the gas discharge are accelerated in the direction toward the auxiliary cathodes 25A, 25B. A part of these ions impinges at a high velocity upon the auxiliary cathodes 25A, 25B and causes a sputtering of the getter material which is deposited on the cathodes 24A, 24B and on other parts of the pump. The other part of the ions flies through the honeycombed auxiliary cathodes 25A, 25B and after being retarded in the electric field between the auxiliary cathodes 25A, 25B and cathodes 24A, 24B, these ions impinge at a reduced velocity upon the cathodes 24A, 24B and are taken up by the getter layers thereon. In order to eliminate the mentioned memory effect which also occurs in this three-electrode pump, the electrodes 26A, 26B are provided at least from time to time with a lower electric potential than the anode 5 so that aside from the sputtering of the titanium also the electrodes 26A, 26B are sputtered. The getter layer, for example, of titanium which is already existing and is formed continuously is then at least interspersed with, and at least partly covered, by the additionally sputtered metal of the electrodes 26A, 26B. The gases which are taken up in the getter layer are thereby prevented from again escaping from this layer and passing back into the pump.

FIGURE 5 finally illustrates diagrammatically the manner of installation of an apparatus in which a high vacuum is produced or maintained by means of a sputtering pump according to FIGURE 2, and it also shows a simplified circuit diagram for controlling the operation of this sputtering pump. Since the parts of this pump are the same as those in FIGURE 2, they are also identified by the same reference numerals as in FIGURE 2 and do not need to be further described.

The pipe socket 2 is connected to the container 30 which may be evacuated by a conventional pump unit 37 through a vacuum line 35 and a tightly closing vacuum valve 36. This part of the apparatus is operated in the conventional manner to effect the original evacuation of the container 30, for example, to a vacuum of 10^{-3} mm. Hg. Thereafter, valve 36 is closed and the vacuum is increased by means of the sputtering pump, for example, to

the maximum value of 10^{-8} mm. Hg which is thereafter substantially maintained. For supervising the pressure, a very sensitive vacuum gauge 38, an ionization vacuum gauge, is connected to the vacuum line 35.

The anode 5 is connected by the line 8 to the positive terminal of a high-tension generator 39 which supplies, for example, 5 kv. The negative terminal of the generator 39 is connected by the line 40 to a switch 41 which disconnects the pump when turned to the position 42. The position 43 of switch 41 is used for the normal operation in which a negative potential is supplied by the line 7 to the pair of getter electrodes 4A, 4B of titanium so that these electrodes are sputtered as cathodes. In the position 44 of the switch, the getter electrodes 4A, 4B are dead. The negative potential is then, however, supplied by the line 9 to the pair of electrodes 6A, 6B which consists of a metal, preferably silver, which is much more easily sputtered. This electrode material is then strongly sputtered and thereby buries the rare gas atoms which are contained in the getter layers of the electrodes 4A, 4B.

The selector switch 41 is actuated by the electric or magnetic drive mechanism 50 which, in turn, is controlled by a control unit 51. This control unit may be operated by hand by the handle 52, while in other cases, for example, when the handle 52 is in the position A, the control unit receives its control impulses from the vacuum gauge 38 and maintains the vacuum automatically.

The control unit 51 is for this purpose set to carry out a certain program:

At a very high vacuum of, for example, 10^{-10} mm. Hg, switch 41 is turned to the position 42. When the vacuum decreases beyond the required operating pressure of, for example, 10^{-8} mm. Hg, by minor amounts of, for example, 3×10^{-8} mm. Hg, the pump is started when the switch is changed to the position 43, and it is again switched off when the pressure drops below the required operating pressure. If this is not attained when the pump has been normally operated for a greater length of time or if the pressure increases rather frequently and especially up to slightly higher pressures due to the memory effect, the control unit moves the switch, for example, for 5 to 10 minutes to the position 44 and then returns it again to the position 43 for the normal pump operation.

The sputtering pump according to the invention is developed from the Penning-type pressure gauge. It may therefore also be employed for vacuum measuring, in which event the current flowing through the pump is used for indicating the existing vacuum. This very advantageous property of the conventional sputtering pump is therefore retained despite the various changes which are made therein in accordance with the invention.

Although my invention has been illustrated and described with reference to the preferred embodiments thereof, I wish to have it understood that it is in no way limited to the details of such embodiments, but is capable of numerous modifications within the scope of the appended claims.

Having thus fully disclosed my invention, what I claim is:

1. A sputtering pump of the character described com-

prising a housing, an anode of cellular honeycomb structure mounted within said housing, a normal cathode means of getter material and an auxiliary cathode means of more easily sputtered getter material symmetrically disposed on opposite sides of said anode, a pair of pole pieces by which a magnetic field is produced, means by which a positive electric potential is supplied to said anode and a negative electric potential is supplied to said normal and auxiliary cathodes, said normal cathode being supplied with a higher negative potential than said auxiliary cathode.

5 2. A sputtering pump as defined by claim 1 in which the getter material of said normal cathode means is titanium, and in which the getter material of said auxiliary cathode means is silver.

15 3. A sputtering pump of the character described comprising a housing, an anode of cellular honeycomb structure mounted in said housing, a pair of normal cathodes of getter material which are symmetrically disposed on opposite sides of said anode, a pair of auxiliary cathodes of more easily sputtered getter material which are symmetrically disposed on opposite sides of said anode, a pair of pole pieces by which a magnetic field is produced, means by which a positive electric potential is supplied to said anode and a negative electric potential to at least one pair of said cathodes.

20 4. A sputtering pump as defined by claim 3 in which said negative potential is supplied to said pair of auxiliary cathodes, and a higher negative potential is supplied to said pair of normal cathodes.

25 5. A sputtering pump as defined by claim 4 in which one of said pair of auxiliary cathodes is interposed between said anode and each of said normal cathodes.

6. A sputtering pump as defined by claim 5 in which said auxiliary cathodes are of cellular honeycomb structure.

30 7. A sputtering pump as defined by claim 6 in which a pair of electrodes of cellular honeycomb structure are provided, one of which is interposed between said anode and one of said auxiliary cathodes and the other of which is interposed between said anode and the other of said auxiliary cathodes, said electrodes having a negative electric potential supplied thereto.

35 8. A sputtering pump as defined by claim 7 in which said auxiliary cathodes are formed of titanium and said electrodes are formed of silver.

9. A sputtering pump as defined by claim 3 in which a pair of electrodes of cellular honeycomb structure to which a negative electric potential is supplied are symmetrically disposed on opposite sides of said anode.
